(57) **CLAIM**

The ornamental design for an anchor pad, as shown and described.

DESCRIPTION

FIG. 1 is an isometric view of the anchor pad of the present invention, illustrated with a portion of the anchor pad shown in broken lines;

FIG. 2 is a top plan view of the anchor pad shown in FIG. 1; FIG. 3 is a bottom plan view of the anchor pad shown in FIG. 1;

FIG. 4 is a rear elevational view of the anchor pad shown in FIG. 1;

FIG. 5 is a front elevational view of the anchor pad shown in FIG. 1; and,

FIG. 6 is a right side elevational view of the anchor pad shown in FIG. 1, the left side view being a mirror image of the illustrated view.

The broken line showing the outer perimeter of the anchor pad is included for the purpose of illustrating portions of the article and forms no part of the claimed design.
